his Attorney

UNITED STATES PATENT OFFICE.

JAMES FRANK JOHNSTON, OF BUCYRUS, OHIO.

TOWEL-RACK.

1,203,352.

Specification of Letters Patent. Patented Oct. 31, 1916.

Application filed August 15, 1914. Serial No. 856,892.

To all whom it may concern:

Be it known that I, JAMES FRANK JOHNSTON, a citizen of the United States, resident of Bucyrus, county of Crawford and State of Ohio, have invented a new and useful Improvement in Towel-Racks, of which the following is a specification, the principle of the invention being herein explained and the best mode in which I have contemplated applying that principle, so as to distinguish it from other inventions.

My invention relates to towel dispensing devices, whereby a succession of clean towel surfaces may be presented to users. The object of the said invention is to provide means of the above described character which will be economical of manufacture and efficient in use.

Said invention consists of means herein-after fully described and particularly set forth in the claims.

The annexed drawing and the following description set forth in detail certain means embodying my invention, the disclosed means, however, constituting but one of various mechanical forms in which the principle of the invention may be applied.

In said annexed drawing: Figure 1 represents a vertical transverse section of a towel rack embodying a towel dispensing apparatus constructed in accordance with my invention. Fig. 2 represents a vertical section of the incasing member showing the interior mechanism in end elevation. Fig. 3 represents a vertical transverse section of the device showing the towel element removed from the rollers. Fig. 4 represents a rear elevation of the mechanism contained within the incasing member. Fig. 5 represents an axial section of the lower towel roller. Fig. 6 is a fragmentary elevation of a detail portion of the mechanism.

The illustrated embodiment of my invention comprises an incasing member 1 within which is mounted, as hereinafter fully described, the towel supporting mechanism. In the illustrated device the said incasing member consists of a back member 2 to which is secured the remainder of said member, the whole forming a box-like inclosure. This incasing member is furthermore preferably formed in two parts, a rear part 3 and a front part 4, which are hinged together so as to be separable at the vertical plane $x-x$, Fig. 1, so that the front portion 4 may be swung outwardly so as to expose

the interior of the incasing member, as will be readily understood. The interior mechanism is all mounted upon the front portion of the incasing member so that when the latter is swung outwardly, such mechanism is completely exposed and readily accessible.

Mounted in bearings 5 secured to the upper portion of the front part 4 of the incasing member is a towel roller 6, Fig. 4. This roller comprises a central shaft 7 upon which is removably secured the hollow sleeve 8. The one end of this shaft is provided with a ratchet wheel 9 of a diameter not greater than the diameter of the shaft 7. This ratchet wheel is engaged by a spring-operated pawl 10 suitably mounted upon the interior of the incasing member. This pawl, as will be readily understood, permits rotation of the roller in one direction (that indicated by the arrow in Fig. 4) and prevents rotation in the opposite direction. The opposite end of this shaft is provided with a sprocket wheel 11 rigidly secured thereto in any suitable manner, and the extreme ends of the shaft are provided with journal portions 12, which directly engage the bearings 5, as shown in said figure. One of these bearings is open at the top, the one on the right, as shown in Fig. 4, whereby the roller may be readily removed therefrom, such bearing being preferably formed as illustrated in Fig. 6, wherein the opening is shown to be located in a lateral and upper position whereby the removal of one end and hence the entire shaft is facilitated. Rigidly secured to this shaft is a pin 13 which engages a helical slot 14 formed in one end of sleeve 8, as shown in Fig. 4. This slot is inclined as shown, the inclination being inward and the direction opposite that of the direction of rotation. The opposite end of this sleeve is formed with a similar slot 14, which, however, does not engage any pin on the said shaft. It will therefore be seen that the removal of the sleeve 8 may be effected by first swinging the front portion 4 of the incasing member upon its hinges so as to expose the interior mechanism, then lifting the end opposite that upon which the sprocket wheel 11 is secured, out of its bearing 5, first suitably disengaging the pawl 10, carrying said end upwardly and outwardly from the said bearing on the incasing member, then turning the sleeve 8 whereby the slot 14 disengages the pin 13. After this turning movement has been effected, the

sleeve may be slid off the disengaged end of the shaft. To prevent the inadvertent disengagement of the opposite end of the shaft from its bearings 5, I prefer to provide a retaining device 15 which may consist of a suitable, bent strip of sheet metal of proper strength which extends upwardly and in the vicinity of the sprocket wheel 11, as shown, and prevents the latter from moving in the direction of the roller's axis, as will be readily understood.

Below the roller 6, having its axis parallel therewith and also mounted upon the front part 4 of the incasing member is a second roller 16 also provided with a ratchet wheel 9 engaged by a second pawl 10 which prevents rotation of the roller in the same direction as such rotation is prevented in the case of the roller 6. This roller 16 also comprises a shaft, 17, and an outer hollow sleeve, 8^a, the latter being in all respects exactly identical in construction with the hollow sleeve 8. The one end of the shaft is provided with the journal portion 18 which is mounted in a bearing member 5^a similar to the bearing member 5 on the right, Fig. 4. This shaft is furthermore provided with a central bore 19 which intersects the opposite end of the shaft, and in this bore is seated a pin 20 whose outer end is formed with the journal portion 21 which engages a second bearing member 5^a. Intermediately of the one end of the bore 19 and the pin 20 is a coil-spring 22 one end of which is secured to the pin 20 and the other end to the interior of the shaft. Mounted upon the outer portion of the pin 20 is a second sprocket-wheel and adjacent to this wheel and on the shaft 17 is secured a pin 24 similar to the pin 13 previously described. This pin engages a slot 25 formed in the corresponding end of the sleeve 8^a, the slot, however, being inclined in the opposite direction as shown. The other end of the sleeve 8^a is formed with a second slot 25 as shown in Fig. 4. A sprocket-chain 26 connects the two sprocket-wheels 11 and 23. A second retaining device 27 is provided adjacent to the sprocket-wheel 23, and the sleeve 8^a may be removed from the shaft 17 in the same manner as the sleeve 8 is removed from its shaft, the retaining device 27 preventing the dislocation of said shaft 17 as previously described in connection with the retaining device 15.

The front member 28 of the incasing member is provided with two horizontal slots 29 29 of a width slightly greater than the width of the toweling 32 which is to be used. This toweling is wound upon the two rollers as shown in Fig. 1, one end being secured to the sleeve 8 by means of suitable pointed projections 30, Fig. 4, suitably secured thereto. From this upper roller the toweling passes outwardly

through the upper slot 29 and then back through the lower slot 29 and around the sleeve 8^a to the lower roller, the pointed projections 31 31 being secured to this latter sleeve as shown in said Fig. 4 for the purpose of securing the other end of the toweling.

In preparing the above described device for operation a detached sleeve 8 is taken, one end of the toweling 32 secured to the pointed projections 30 and rolled upon said sleeve. One end of the upper shaft 7 is then removed as previously described and the sleeve slipped thereon, causing the inner slot 14 to engage the pin 13. The disconnected end of the shaft being then replaced and the pawl 10 being caused to engage the ratchet-wheel 9, the outer end of the toweling is passed through the slots as previously described and then secured to the sleeve 8^a of the lower roller, the pointed projections 31 being used for so securing this end. The lower roller is now rotated in the direction indicated by the arrow in Fig. 1 so as to maintain the toweling 32 in a taut condition as shown in full lines in Figs. 1 and 2. A portion 33 of such toweling is thus exposed upon the exterior of the incasing member. The front portion 4 of the latter is then closed and secured to the rear portion 3 by any suitable locking device.

The device as thus far described is now in a position for use. When it is desired to use a portion of the toweling, the exposed portion 33 is grasped at the sides and pulled outwardly. This pulling movement rotates the upper roller in the direction indicated by the arrow in Fig. 1, the rotatory movement being transmitted from the toweling to the sleeve 8, then to the pin 13, to the shaft 7 and thus to the sprocket-wheel 11. This rotation of the latter is transmitted by the sprocket-chain 26 to the lower sprocket-wheel 23 which rotates the shaft 17. The rotation of the latter is transmitted to the pin 20, the rotation of the latter winding up the coil-spring 22. During this operation the sleeve 8^a is held stationary by the lower pawl 10, the tension on the toweling tending to rotate the said sleeve in the direction opposite that indicated by the arrow and thus operating in opposition to the resistance created by the engagement of the said pawl and the lower ratchet-wheel 12. The exposed portion of the toweling is thus increased and may then be used. Upon its release the spring 22 rotates the shaft 17 in the direction indicated by the arrows in Figs. 1 and 4 and said shaft, through the medium of the pin 24 drives and rotates the sleeve 8^a, thus winding in the lower portion of the toweling and drawing the exposed portion inwardly into the incasing member until a condition of tautness is again established.

The above operation is repeated until all of the toweling is unwound from the upper roller, whereupon the incasing member is opened, the one end of the lower shaft disengaged and the sleeve 8^a removed, together with the soiled toweling. The device is then supplied with a fresh roll of toweling, the latter being applied to the upper roller as before described, and the above described operations are repeated.

In order to facilitate the ready grasping of the exposed portion of the toweling, I prefer to apply a projecting member 34, Fig. 1, to the exterior of the front 28 of the incasing member which holds the toweling outwardly from the latter a short distance whereby the fingers of the operator may be inserted underneath, as will be readily understood, for the purpose of drawing the towel outwardly as previously described. This projecting member may be of any suitable dimensions such as may be found will effect the purpose above described, and may be of any suitable construction or material, one requisite being, however that it shall not present any sharp edges or points which would catch and thus injure the fabric of the toweling.

Having fully described my invention, what I claim and desire to secure by Letters Patent is:—

1. In a device of the class described, the combination of an incasing member; a roller mounted in the latter; a towel wound upon said roller; a second roller mounted in said member and comprising a roller shaft and hollow sleeve mounted thereon to which latter one end of said towel is secured; a spring having one end connected with said shaft and the other end connected with said first-named roller; and means connecting said two rollers whereby the rotation of the first-named roller will energize said spring.

2. In a device of the class described, the combination of an incasing member; a roller mounted in the latter and adapted to receive a roll of toweling; a second roller mounted in said member and comprising a hollow roller shaft and sleeve mounted thereon to which one end of said towel is adapted to be secured; a coil-spring in said hollow shaft and having one end secured thereto; rotatable means connecting the

other end of said spring with said first-named roller; and means connecting said two rollers whereby the rotation of the first-named roller will energize said spring.

3. In a device of the class described, the combination of a roller suitably mounted; a second roller having its axis parallel with that of said first-named roller and having a hollow shaft; a coil-spring in said hollow shaft and having one end secured thereto; a suitable bearing for one end of said shaft; a pin rotatably mounted in and projecting from the other end of said shaft and secured to the other end of said spring; a suitable bearing for the projecting end of said pin; and gearing connecting said first-named roller and the said shaft.

4. In a device of the class described, the combination of an incasing member; means within the latter for receiving and holding a roll of toweling; said incasing member being provided with two slots; said two slots being arranged so that said toweling may extend from the interior through one of said slots to the exterior of the casing and from such exterior back into the interior through the other slot; means for retaining such exteriorly-extending towel portion in a taut condition; and an outwardly-projecting device secured to the exterior of said casing and located between said slots for holding such exteriorly-extending portion of such toweling away from the casing.

5. In a device of the class described, the combination of a roller suitably mounted and comprising a shaft and removable hollow sleeve mounted thereon so as to be adapted to drive said shaft; a second roller suitably mounted and having its axis parallel with that of said first-named roller; said second-named roller comprising a shaft and removable hollow sleeve mounted thereon so as to be adapted to be driven by said shaft; and means connecting said two rollers whereby the rotation of the first-named thereof will effect the automatic rotation of the shaft of the second-named roller.

100

Signed by me, this 17th day of May, 1913.

JAMES FRANK JOHNSTON.
